THOMAS METZLER, OF WOOSTER, OHIO.

Letters Patent No. 96,136, dated October 26, 1869.

IMPROVEMENT IN PUMPS.

The Schedule referred to in these Letters Patent and making part of the same.

To all whom it may concern:

Be it known that I, THOMAS METZLER, of Wooster, in the county of Wayne, and State of Ohio, have invented a new and useful Improvement in Pumps; and I do hereby declare that the following is a full, clear, and exact description thereof, which will enable others skilled in the art to make and use the same, reference being had to the accompanying drawings, forming part of this specification.

This invention relates to improvements in pumps designed to provide a simple and efficient arrangement of the same for elevating water from wells, cisterns, &c.

It consists in an arrangement of means for operating a collapsing-bulb pump when suspended in or near the water of a well or cistern to protect it from frost, as hereinafter more fully specified.

The drawing represents a perspective view of my improvement.

A represents a pump, consisting of a collapsing-bulb, provided with valves, not shown in the drawings, and such as now commonly used.

B represents the suction-pipe, and
C, the discharge-pipe.

I suspend this pump on a platform, C', in the well, preferably near the water, to prevent freezing, and on the said platform, or in any preferred manner, I arrange a pair of squeezers, D, to act on the bulb, for compressing it. In this instance, the squeezers D are arranged on each side of the bulb, hinged at the bottom, and provided with bent arms, E, connected, by links,

F, to the working-rod G, which is carried to the top of the well, and arranged to be operated by a lever or other suitable means, to give it vertically-reciprocating motion.

The elevation of the rod will draw the squeezers together, compressing the bulb, and forcing the water up through the pipe C.

The opposite movement allows the bulb to expand, and draw the water into it from below.

I propose to support a platform, H, on suitable bars or braces, I K, rising up from the lower platform C', whereon the pump and squeezers are placed; which said platform H serves for supporting the rod G and pipe, and connects the whole together in a portable apparatus conveniently arranged to be set into a well or cistern, with the said platform H at the top for closing the mouth of the well or cistern, and for the operator to stand on while pumping.

Having thus described my invention,

What I claim as new, and desire to secure by Letters Patent, is—

1. The combination, with the pump A, of the squeezers D, arranged for operation substantially as specified.

2. The platforms C' and H, connected by braces or supports I K, and combined with the pump and operating-devices, substantially as specified.

THOMAS METZLER.
